UNITED STATES PATENT OFFICE.

SAMUEL HAVERSTICK, OF CHICAGO, ILLINOIS.

1,121,182.

LINOLEUM.

Specification of Letters Patent.

Patented Dec. 15, 1914.

Application filed June 11, 1913. Serial No. 772,978.

To all whom it may concern:

Be it known that I, SAMUEL HAVERSTICK, citizen of the United States, residing at Chicago, in the county of Cook and State of Illinois, have invented a certain new and useful Improvement in Linoleum, of which the following is a full, clear, concise, and exact description, reference being had to the accompanying drawings, forming a part of this specification.

My invention relates to linoleum and includes a product in which there is provided an underlying layer of paper upon which the linoleum substance is mounted and to which such substance adheres. This underlying sheet of paper is preferably provided with a series of parallel strings which are disposed longitudinally of the linoleum strip and are preferably so incorporated within the paper as to be concealed, excepting where the product is cut in cross section. These strings serve to prevent the product from being torn transversely, it having been found that no provision is necessary to guard against the tearing of the product longitudinally thereof. In order further to guard against the tearing of the product after it issues from the machinery the stretches of string which margin the outer longitudinal edges of the linoleum strip are desirably heavier than the remaining stretches of string, each being preferably formed of a double string, each of a size similar to the remaining strings. The material of which the strings are made is preferably non-metallic, the material employed being desirably linen thread, though the invention is not to be limited to the nature of the threads employed. The paper is preferably made water proof and this result is desirably accomplished by providing the bottom face of the paper with a layer of water proof paint, though I do not wish to be limited to this method of making the paper water proof. In order that there may be proper cohesion between the paper and the layer of linoleum applied thereto the paper is uncalendered so as to permit the fibers thereof freely to project therefrom so as readily to become incorporated with the applied linoleum.

I will explain my invention more fully by reference to the accompanying drawing showing the preferred embodiment thereof and in which—

a plane in which the parallel threads are disposed, (line 1 1 of Fig. 2) an intermediate portion of the product being removed, the figure being taken on a reduced scale excepting for the size of the threads which is necessarily exaggerated in this figure; Fig. 2 is an end view on an exaggerated scale; Fig. 3 is a detail of construction taken on line 3 3 of Fig. 1 but on a still further exaggerated scale; and Fig. 4 is a sectional view of the paper taken on a much exaggerated scale and indicating its fibrous nature.

Like parts are indicated by similar characters of reference throughout the different figures.

The layer 1 of linoleum is applied, while in plastic condition and of a temperature having substantially 90° Fahrenheit, to the top face of the underlying strip of paper 2, and as the paper is uncalendered the fibers projecting from the upper side thereof will become thoroughly incorporated with the adjacent portion of the linoleum layer so that when the linoleum has cooled the linoleum and paper will form component parts of an integral product which will not be subject to separation at their adjacent faces. A very suitable paper for this purpose is that commercially known as felt paper. As the uncalendered paper is highly hygroscopic I make it water proof preferably by the application of a bottom coating of water proof paint indicated at 3. The thickness of the entire product is usually either an eighth of an inch or a quarter of an inch. The relative thicknesses of the linoleum and the paper layers may be substantially as illustrated in Fig. 3.

Owing to the fact that the uncalendered paper lacks necessary tensile strength, an inherent advantage which is sacrificed to permit the fibers of the paper to become incorporated in the linoleum, the necessary tensile strength is supplied by a supplemental means preferably in the form of linen threads 4 which extend longitudinally of the strip of linoleum which is made in the factory in variable lengths say thirteen hundred fifty yards and which is supplied to the trade in lengths of about ninety feet. The linen thread employed is manufactured by the Clark Thread Works and is preferably No. 60. These threads may be spaced three inches or so apart and are preferably continuous from end to end of the

2
 The product which I have evolved is superior to the product at present upon the market in many respects. The product is very flexible and pliable without danger of cracking and without liability of separating the layer of linoleum from its foundation. It is not likely to buckle or chip and may readily be laid perfectly flat upon the floor. Water, not being able to attack the linoleum foundation because of its water proof nature, cannot cause this layer to shrink, expand or rot so that the superposed layer of linoleum is thoroughly protected from the water.

15 By the term "uncalendered paper" I mean paper whose face disposed next the layer of linoleum is not smooth or calendered but is rough because of the fibers projecting therefrom so as to be adapted for incorporation with the linoleum.

20 Having thus described my invention I claim as new and desire to secure by Letters Patent the following:

1. A new article of manufacture including a layer of linoleum and a layer of uncalendered fibrous paper upon which the layer of linoleum is superposed, fibers at the upper surface of the paper projecting into and being incorporated with the adjacent portion of the linoleum layer to constitute the paper and linoleum an integral whole.

2. A new article of manufacture including a layer of linoleum and a layer of uncalendered fibrous paper upon which the layer of linoleum is superposed, fibers at the upper surface of the paper projecting

into and being incorporated with the adjacent portion of the linoleum layer to constitute the paper and linoleum an integral whole; and a coating of water-proof material supplied to the bottom face of the paper.

3. A linoleum or inlay floor covering of the character described comprising a plastic mass, a paper foundation therefor, and means interlocking the said mass with the said foundation, consisting of fibrous projecting portions on the upper surface of the paper, extending in all directions, and embedded in the plastic to a substantial extent to anchor the latter throughout and from correspondingly all directions to the paper foundation.

4. A linoleum or inlay floor covering of the character described comprising a plastic mass, a paper foundation therefor, and means interlocking the said mass with the said foundation consisting of fibrous projecting portions on the upper surface of the paper, extending in all directions, and embedded in the plastic to a substantial extent to anchor the latter throughout and from correspondingly all directions to the paper foundation, in combination with a water-proof coating on the exposed surface of the said paper foundation.

In witness whereof, I hereunto subscribe my name this ninth day of June A. D., 1913.

SAMUEL HAVERSTICK.
